UNITED STATES PATENT OFFICE

PIERRE JOURNOUD, OF LYON, FRANCE, ASSIGNOR TO L. J. HYAMS AND COMPANY, OF
NEW YORK, N. Y.

DESIGN FOR A PRINTED TEXTILE FABRIC OR SIMILAR ARTICLE

Application filed November 23, 1932. Serial No. 46,126. Term of patent 3½ years.

To all whom it may concern:

Be it known that I, PIERRE JOURNOUD, a citizen of France, and a resident of Lyon, France, have invented a new, original, and ornamental Design for Printed Textile Fabric or Similar Article, of which the following is a specification, reference being had to the accompanying drawing, forming part thereof.

The figure is a plan view of a printed textile fabric or similar article, showing my new design.

The dot and dash lines on the drawing outline the design unit, which unit is repeated in regular succession as indicated by the extensions beyond the unit boundaries.

I claim:

The ornamental design for a printed textile fabric or similar article, as shown and described.

PIERRE JOURNOUD.
